UNITED STATES PATENT OFFICE.

FRANK FENTON, OF AKRON, OHIO, ASSIGNOR TO THE MILLER RUBBER COMPANY, OF AKRON, OHIO, A CORPORATION OF OHIO.

TUBE-ROLLING MACHINE.

1,197,192.

Specification of Letters Patent.

Patented Sept. 5, 1916.

Application filed June 1, 1916. Serial No. 101,089.

To all whom it may concern:

Be it known that I, FRANK FENTON, a citizen of the United States, and resident of Akron, Ohio, have invented certain new and useful Improvements in Tube-Rolling Machines, of which the following is a specification.

My present invention relates to improvements in machines for producing convolute 10 wound tubing and is more especially designed for manufacturing rubber tubing for use as inner tubes for pneumatic tires, though not limited to such use.

In devising my present invention I have 15 aimed to provide a machine which will make with speed and accuracy tubes of this class, which shall be free from blisters and other defects heretofore frequently found in machine made tubes.

I have further aimed to provide a machine which shall be economical and durable and capable of easy manipulation.

The invention includes the novel features of construction and arrangement and combination of parts hereinafter described and particularly defined by the appended claims.

An embodiment of the invention is illustrated in the accompanying drawings, in which,

Figure 1 is a plan view of such a machine partly broken away. Fig. 2 is a front elevation also partly broken away, and, Fig. 3 is an end elevation.

According to my present invention I support the sheet of rubber composition from which the tube is to be formed by winding in convolute form upon a mandrel, upon a flat supporting plate or platen with the edge of the sheet projecting beyond the edge of 35 the plate, such projecting edge being treated or coated to make it adhesive. Thereafter the supporting plate is moved by a suitable conveyer until said adhesive edge is brought into contact with the surface of a floating 40 cylindrical mandrel which is sustained in proper position and rotated by a plurality of rollers, one of which may be power driven and the others rotated by frictional contact. After the supporting plate has been moved 45 sufficiently to cause the projecting edge of the sheet to adhere to the mandrel further movement of the said plate is arrested and the sheet drawn therefrom by the rotation of the mandrel, the frictional contact of the 50 sheet with the supporting plate secures suffi-

cient tension to effectually prevent the rubber from forming a bank in front of the mandrel and thereby entrapping air and forming blisters or creases.

Referring by reference characters to the drawings, which show a preferred form of apparatus for carrying out the operation above referred to, the numeral 1 designates a machine frame which may be of any construction necessary to supporting the working parts of the machine.

2, 2' are parallel rails supported at opposite ends of the frame 1, and carrying at the rear ends pillow or bearing blocks 3, 3'. Rails 2, also support at their forward ends 70 bearings 4, 4', which are slidably adjustable along rails 2. Rails 2, also support brackets 5, 5' at their forward extremities. Brackets 5, 5' support adjusting screws 6, 6', for the purpose of adjusting bearings 75 forward and backward along rails 2. Bearings 4, support an idle roller 7, said roller 7, being provided with helical ridges 7^a and 7^b, the ridges 7^a forming a right hand helix and extending from the right hand end of 80 the roll to its center, and the ridges 7^b forming a left hand helix extending from the left end of roll 7, to its center. Brackets 3, 3' support a roll 8, at the rear of the machine, said roll 8 being provided at one end 85 with a clutch 9, carrying a pulley 10, and having suitable shifting mechanism such as hand lever 11, connected thereto, for the purpose of connecting said roll 8, to any convenient source of power. The clutch 9, 90 may be of any standard construction and is representative of any suitable means for applying or disconnecting the power from said roll 8, at the operator's will. An endless conveyer 12, of a width which is longer than 95 the longest tube which I desire to make, encircles rolls 7 and 8. From the foregoing description it will be readily seen that this conveyer may be driven by means of the roll 8, and any slack therein may be taken up 100 by the adjustable bearings 4, 4' and their adjusting screws 6, 6' in which roll 7 is journaled. The purpose of the afore described ridges 7^a and 7^b on roll 7 is to keep the conveyer belt 12 in proper alignment. 105 The upper surface of this conveyer belt 12 travels from the front to the rear of the machine.

Located on the rails 2, between the bearings 4, 4' and bearings 3, 3' are bearings 110

13, 13'. An idle roll 14 is journaled in said bearings 13, 13', in such a position that the upper portion of conveyer belt 12 passes over the top of roll 14, and the under portion passes below the roll 4. Rails 2 also support a table 15, which extends beneath the upper surface of conveyer belt 12, from roll 7, at the front of the machine to roll 14, at the rear of the machine, said table 10 extending from rail 2 to rail 2', and being somewhat wider than the conveyer belt 12. Table 15, is provided with raised parallel strips 16, 16', extending from the front of the machine toward the rear.

15 Guided between strips 16, 16' is a sheet supporting plate or platen 17. Strips 16, 16' are provided with stops 18, 18' at their forward ends, and stops 19, 19' at their rear ends. The sheet supporting plate or 20 platen 17 rests upon the conveyer belt 12, and is guided between strips 16, 16' and upon motion being applied to the conveyer belt 12, the plate or platen 17 is carried rearwardly of the machine, by frictional contact with the conveyer belt, until prevented from further motion by its contact with stops 19, 19'. The platen 17 is provided with hand holes 17^a, by which the operator 25 may pull the platen toward him until prevented from further motion, by stops 18, 18'. Pedestals 20, 20' rigidly supported from the frame 1, of the machine, carry plates 21, 21', 22, 22'. Rigidly supported in plates 21 and 22, are rods 23, fixed in vertical parallel relation. A cross-head 24, slidably mounted on rods 23, is formed with a threaded boss 24^a, which engages a screw 25. The upper end of the screw 25 is journaled 30 in a boss 21^a, formed in the center of plate 21. Screw 25 also carries above boss 21^a a beveled gear 26. The same description will apply to like parts at the opposite end of the machine.

Plates 21 are formed with a vertical projection carrying a horizontal boss 21^b. Plate 21^b is also provided with a similar boss 21^b, the two bosses 21^b and 21^b being in horizontal alinement and forming bearings for a horizontal shaft 27, journaled thereto. Shaft 27 carries fixed bevel gears 28, 28' meshing with bevel gears 26, 26', previously described. Rotation imparted to shaft 27, will raise or lower cross-heads 24, 24' in unison, through bevel gears 28, 28' and screws 25, working in cross-heads 24. Shaft 27 also carries a fixed pulley 28, and idle pulleys 29 and 30, adjacent thereto on either side of said fixed pulley 28. A straight belt 31, normally surrounds the pulley 30, and a cross belt 32, normally surrounds the pulley 29. A bracket 33 supported on plate 21 carries sliding rod 34, provided with fixed shifting forks 35 and 36. Rod 34 is also provided with a shifter lever 37, by which it may be moved horizon-

tally, and positions of belts 31 and 32, which are encircled by shifting forks 35 and 36, may be changed so as to bring either belt upon the fixed pulley 28, thus causing rotation of the shaft 27 and consequently raising or lowering of the cross-heads 24, 24'. Rods 23 also carry a second cross head 38, slidably mounted thereon. Cross-head 24 is provided with bosses 24^b and 24^c, forming bifurcated bearings, surrounding the rods 23, by which it is guided in its vertical movement. The cross-head 38 is also provided with bosses 38^a and 38^b also forming bifurcated bearings, by which cross head 38 is guided in its vertical movements by rods 23. Cross-heads 24 and 38 and rods 23 are so assembled that bosses 38^a, come between bosses 24^b and 24^c. In this position an upward movement of cross-head 24 will cause boss 24^c to oppose 38^a and thereby raise cross-head 38. Also a downward movement of cross head 24, will carry cross-head 38 until it makes contact with some fixed object, preventing the motion of cross head 38. Cross-head 24 will then proceed in its downward movement without effecting the cross head 38. Cross-head 38 is provided with a horizontal slot 38^c. Located in slot 38^c, are horizontal studs 39, which may be moved toward the front or rear of the machine within the limits of said slot 38^c for the purpose of adjustment. Studs 39, are locked in position by nuts 40, threaded thereon. Studs 39 carry idle rollers 41, mounted on the ends thereof. Cross-head 38 is also provided with idle rollers 41, supported in like manner.

Referring to Fig. 3, 42 is a hollow tube or so-called building pole or mandrel, upon which the rubber tubes are built. Said pole 42 rests upon the surface of belt 12, slightly to the rear of the vertical center line of roll 14. Idle rollers 41, are so adjusted as to be equally distant from the center of the pole 42. It is apparent that if the rolls 41, are now lowered until the weight of cross heads 38, 38' rest on pole 42, which is supported by belt 12, which in turn is supported by idle roll 14, the pole 42, will be so surrounded that motion imparted to belt 12, can only cause a rotation of pole 42, rollers 41, preventing the displacement of pole 42.

The operation of the above described machine is as follows: The operator of the machine, by means of shifter lever 37, causes rotation of the shaft 27, and the corresponding elevation of the rollers 41, 41'. After the rollers 41, 41' have been elevated above the belt 12 at sufficient distance to allow the building pole or mandrel 42 to pass between rollers 41, 41', and belt 12, the shifter lever 37 is moved to such a position as to stop further elevation of said rollers 41, 41' and an empty inner tube pole 42, is now placed in the proper position upon belt 12, pref-

erably from the rear of the machine. Shifter lever 37 is then again operated so as to cause the rollers 41, 41' to descend and make contact with the end of the inner tube pole, pressing said pole against the portion of the belt 12, slightly to the rear of the said idle roll 14, supporting said belt. Lowering of cross-heads 24, 24' is continued until the operator sees that bearings 24' of cross head 24 have departed from contact with boss 38' of cross-head 38, when the entire weight of the rolls 41 and cross heads will be supported by the mandrel which in turn is supported and rotated wholly by the portion of the conveyer belt adjacent the side roll 14. The shifter lever is then shifted to its central position, at which time motion of cross head 24 ceases. It will be noted that the only downward pressure exerted upon the inner tube pole is now due to the weight of cross-heads 38, 38' and their associated parts. Said cross-heads 38, 38' are proportioned in weight in order to give the proper amount of pressure between the inner tube pole 42, and the idle roll 14. Continuing the operation of the machine, the operator now grasps the platen 17, by the hand holes 17', and pulls it toward the front until it comes in contact with the stops 18, 18'. The sheet of rubber which is intended to be rolled upon the mandrel or inner tube pole, is now placed upon the platen 17, in such a position that the edge of the rubber nearest the inner tube pole overlaps the platen 17, by a small amount, and lays upon the belt conveyer 12. It will be remembered that the platen 17, itself also lays upon the belt 12. The upper side of the projecting edge of this rubber has been caused to become sticky, by the application of some rubber solvent. The operator now throws the clutch lever 11, which controls the application of power to the conveyer belt 12, through roller 8. The upper surface of the conveyer belt 12, moves rearwardly toward the inner tube pole or mandrel carrying with it the platen 17, and the superimposed sheet of rubber, from which the inner tube is to be made. The aforesaid projecting edge of this sheet of rubber passes beneath the inner tube pole and is stuck thereto by its cemented edge, so that the rubber leaves the conveyer belt 12 and follows the motion of the inner tube pole, thereby rolling itself upon the inner tube pole. Immediately after the projecting edge of the rubber has entered between the inner tube pole and the conveyer belt 12, the platen 17 comes in contact with stops 19, 19' preventing its further forward motion. The conveyer belt 12 proceeding on its motion draws the remaining portion of the rubber sheet over the top of the now stationary platen 17, and the slight friction between the rubber sheet and the platen 17 causes the rubber sheet to be drawn upon the inner tube pole with a slight tension, which effectually prevents the rubber from forming a bank in front of the inner tube pole and thereby trapping air and forming blisters and creases in the tube. The object in placing the inner tube pole slightly to the rear of the center of the idle roller 14, is to take care of any irregularities in the inner tube poles as these poles are often slightly bent from continued abuse. After the rubber sheet has been entirely wound upon the inner tube pole, forming a tube of several plies, the shifter lever 37 is again operated so as to elevate the rollers 41, 41'. After the rollers 41, 41' have been raised a sufficient distance for the pole to pass beneath them, the entire tube pole with the finished inner tube thereon will be carried to the rear of the machine, the conveyer belt 12, thus serving as a conveyer belt, to carry the pole away, and the roller 8 may be located at any convenient distance from the rolling mechanism, its only purpose being to support and drive the belt 12. The clutch lever 11 can now be operated, stopping belt 12, another tube placed in the proper roll in position, and the afore described operation is repeated. Rollers 40 and 41 are preferably made in the shape of very short rollers to contact with the end portions only of the mandrel, the space between said pairs of rolls 40 and 41 allowing for any warping or irregularity in the mandrel.

What I claim is:—

1. In a tube winding machine, a floating mandrel, a plurality of rolls relatively movable toward and from each other and adapted to retain the mandrel therebetween, means for rotating said rolls and mandrel, a platen for supporting the sheet to be wound with its edge projected beyond the edge of the platen, and means whereby the platen is moved forward until the projected edge of the sheet is applied to the mandrel and is then arrested to permit the sheet to be drawn from the platen. 100
2. In a tube winding machine, a floating mandrel, a plurality of rolls relatively movable toward and from each other and adapted to retain the mandrel therebetween, means for rotating said rolls and mandrel, a platen for supporting the sheet to be wound with its edges projected beyond the edge of the platen, friction means for moving the platen toward the mandrel until the projected edge of the sheet is applied to the mandrel and stops for arresting the movement of the platen. 115
3. In a tube winding machine, a floating mandrel, endless moving mandrel supporting and sheet conveying means, a pair of yieldable rollers for bearing upon the upper sides of the mandrel, a platen for supporting the sheet to be wound with its edge projected beyond the edge of the platen, said platen 120

being supported by said conveying means and moved wholly by its frictional contact therewith and stops for arresting the movement of said platen.

- 5 4. In combination an endless conveyer belt, with means for driving it, an idle roller operating beneath an intermediate portion of the upper half of said conveyer belt, a pair of yieldable rollers located above said belt in proximity to said idle roller, a mandrel supported above said conveyer belt in proximity to said idle roller and pressed upon by said yieldable rollers and lying in the bite formed therebetween, means for 10 positively raising and lowering said pair of rollers, a sheet supporting platen resting upon said conveyer belt and stops for arresting the movement of the platen.
- 5 5. In combination endless moving sheet 20 conveying and mandrel supporting means, a vertically movable roll carrier above said means carrying a pair of mandrel retaining rolls, a cylindrical mandrel confined between said sheet conveying and mandrel supporting means and the bite between said pair of rollers, and roll elevating and lowering means having a lost motion connection with said roll carrier.

- 6 6. In combination endless moving sheet 30 feeding and mandrel supporting means, a mandrel supported thereby, guide posts, cross-heads supported by said guide posts, a pair of idle rolls carried by said cross-heads, the upper side of said mandrel resting in 35 the bite of said idle rolls, a second pair of cross-heads movable on said guides and having a lost motion connection with the first named cross-heads and means for raising and lowering said second named cross-heads.
- 40 7. In combination an endless moving conveyer belt, an idle roll supporting an intermediate portion of said belt, a roll carrier above said belt in proximity to said idle roll, and a pair of idle rolls carried by said idle 45 roll carrier with the median vertical line between said idle rolls in rear of the axis of the said first named idle roll, and a mandrel above said conveyer belt and engaging the bite of said pair of idle rolls.

- 50 8. In combination an endless moving conveyer belt, an idle roll supporting an intermediate portion of the belt, a roll carrier

above said belt in proximity to said idle roll, a pair of idle rolls supported by said carrier so that a vertical line drawn centrally between said rolls will pass in rear of the axis of said first named idle roll, and means for adjusting the rearmost of said pair of rolls toward and from its mate, and a mandrel engaging the bite of said pair of idle rolls. 55

9. In combination an endless conveyer belt and means for driving it, an idle roll supporting an intermediate portion of said belt, a floating mandrel supported by said belt, a pair of yielding juxtaposed presser rolls 60 with the bite of which said mandrel engages, parallel guides in proximity to said conveyer belt, a sheet supporting platen retained by said guides at its edges and having frictional contact with the conveyer belt and 70 stops for engaging opposite edges of said platen for limiting the movement thereof.

10. In combination, a lower roll, a pair of upper rolls, a mandrel supported between the bite of said upper rolls and said lower 75 rolls, a sheet carrier adapted to support a sheet of material with its edge projected beyond the edge of said carrier, and means for moving said carrier until said projected edge contacts with said mandrel and then 80 arresting said carrier.

11. In combination a lower roll, a pair of short upper rolls located near each end of the lower roll, a mandrel supported above said lower roll and having its ends lying in 85 the bites of said upper rolls and pressed upon thereby, a sheet carrier adapted to support a sheet of material with its edge projected beyond the edge of said carrier, and means for moving said carrier until said 90 projected edge contacts with said mandrel and then arresting it.

12. In a tube rolling machine, an endless moving surface, a mandrel supported thereby and a pair of yielding presser rolls bearing upon the mandrel at or near each end thereof. 95

In testimony whereof, I affix my signature.

FRANK FENTON.
